SIDE RAIL FOR BEDS

Alma W. Schutzer, San Francisco, Calif.

Application April 24, 1948, Serial No. 22,999

3 Claims. (Cl. 5—331)

1

This invention relates to improvements in hospital beds and more particularly to side rails for such beds.

An object of my invention is to provide an improved side rail for hospital beds embodying novel rail supporting means attachable to a side of a bed frame which makes it possible to support the rail either in an upstanding operative position or in a concealed out-of-the-way position underneath the springs of the bed.

Another object of my invention is to provide an improved side rail of the type characterized which is arranged for manipulation in a narrow space without the necessity of swinging the rail outwardly through a wide arc when moving it from an upstanding operative position to a concealed position beneath the springs of the bed, or when moving the rail in a reverse direction from beneath the bed to an upstanding operative position.

Other and further objects of my invention will be pointed out hereinafter, or will be obvious to one skilled in the art upon an understanding of the present disclosure. For the purpose of this application I have elected to show herein certain forms and details of a side rail for beds embodying my invention. It is to be understood, however, that the embodiment of my invention herein shown and described is for illustration purposes only and that therefore it is not to be regarded as exhaustive of the variations of the invention.

In the accompanying drawings:

Fig. 1 is a perspective view of a bed having side rails of the type embodying my invention mounted thereon;

Fig. 2 is a side elevational view of the same;

Fig. 3 is a diagrammatic end view of the bed, showing one of the side rails in an upright raised position, and the other rail at the opposite side of the bed in a lowered position, preparatory to its being swung into a concealed position under the bed; and

Fig. 4 is an enlarged sectional view taken on the line 4—4 of Fig. 3, showing the latch means for holding the side rails in supported positions under the bed.

The bed with which my invention is used embodies the usual bed frame comprising a foot portion 1 having corner posts 2 and a head portion 3 having corner posts 4. The springs and mattress (not shown) are supported on the bed frame in the customary manner. Side rails 5 adjustably mounted at the sides of the bed frame are each arranged to be operatively positioned in

2

an upright position as shown on Fig. 1 of the drawings, or in a concealed out-of-the-way position beneath the bed. Since the side rails are similarly supported at the sides of the bed frame, a description of the supporting means for one of the rails will suffice for both.

Secured in parallel relation to a corner post 4 is a substantially vertical guide rod 6 which is slightly longer than the width of its associated side rail 5. The guide rod 6 has threaded end extensions 7 which extend inwardly through the post 4. A collar 8 fixed on each extension 7 abuts an outer side of the post while a nut 9 engaging with the threaded portion of the extension abuts the opposite inner side of the post. It will be noted that the guide rod 6 is securely supported in spaced substantially parallel relation to its associated post. At the lower end of the bed frame is provided a similar arrangement for supporting the opposite ends of the side rails. Secured to a corner post 2 is a substantially vertical guide rod 10 which is about the same length as the guide rod 6. The lower end of the guide rod 10 has an inwardly disposed threaded extension 11 at its lower end which extends inwardly through the post 2, and a collar 8 and a nut 9 of the kind heretofor described secures the said extension to the post. The upper end of the guide rod 10 extends inwardly at 12, downwardly at 13 and then inwardly again at 14. The inwardly extending portion 14 is threaded and is secured in the same way by a collar 8 and a nut 9 to the post 2. The upper end of the guide rod 10 is formed with extensions 12 and 13 in order that the said rod may be supported at substantially the same level as the guide rod 6 and in parallel relation thereto. The foot portion 1 of the bed frame is substantially lower than the head portion 3, thereby making it necessary to form the guide rod 10 with the extensions 12, 13 and 14 in order that the side rail may be arranged either in its normal up-right position or in its out-of-the-way position beneath the bed.

Secured at each end of the side rail 5 near the top edge thereof is a projecting eye member 15 through which the guide rods 6 and 10 slidably extend. Slidably mounted on the lower edge of the side rail 5 and arranged to be projected from the ends of the said rail are bifurcated members 16 which are adapted to engage with the guide rods 6 and 10. The bifurcated members are arranged so they can be extended beyond the ends of the side rail 5 to engage with the guide rods 6 and 10, or they may be retracted toward each other to permit their disengagement with re-

spect to the said guide rods. When extended, as shown in Fig. 1, the bifurcated members 16 are arranged to engage with the inwardly disposed lower extensions 7 and 11 of the guide rods 6 and 10, respectively, and the rail 5 is then supported in an upright operative position. The eye members 15 engaging with the guide rods 6 and 10 prevent the rail from becoming displaced from its upright position when it is so supported by the bifurcated members 16.

When it is desired that the rail be positioned in a concealed out-of-the-way position, the bifurcated members 16 are moved backwardly from engaging positions with respect to the guide rods 6 and 10. The rail may then be lowered in a vertical plane until the eye members 15 engage with the lower inwardly disposed extensions 7 and 11 of the guide rods. The rail is then swung inwardly as indicated by the arrow in Fig. 3 to a substantially horizontal position under the bed. It will be noted that the rail, when moved from its operative position to one where it is concealed, and vice versa, does not have to be swung outwardly through an arc. Thus a bed equipped with the present invention does not require much additional side space for the adjustment and movement of its side rails.

The side rails 5 are supported in concealed positions by means of a pair of independently operable keepers 17 which are pivotally supported in a case 18 in a central position on the foot portion 1 of the bed frame. The keepers 17 when in their normal forwardly projecting position, extend under the side rails 5 and thereby support them in substantially horizontal positions, as shown in Fig. 4. A spring 19 connected at its ends to the keepers 17 normally maintain them in positions whereby their forward ends project from the case 18 to positions for supporting the rails. Cords, chains or cables 20 connected to the keepers 17 serve to turn the latter about their pivots and thereby retract their forward ends from supporting positions with respect to the rails. Each keeper 17 is capable of independent operation, and the spring 19 automatically returns the keepers to their normal positions after they have been retracted by an operator who has manipulated either or both of the cords 20.

It is to be noted that the present invention may be applied to various types of beds now in use, it only being necessary to drill the necessary holes in the bed posts for the attachment of the guide rods. It is also to be noted that the present invention is well adapted for use with children's beds or cribs.

As shown by the broken lines in Fig. 3 a rectangular extension member 21 may be supported above the foot portion 1 of the bed frame by means of the extensions 13 of the guide rods 10. In this arrangement eye members or other means are used to connect the opposite ends of the rectangular member 21 with the extension 13.

What I claim is:

1. In a bed having upright corner posts, a pair of substantially parallel upright guide rods secured to and arranged in spaced relation to the posts, the said guide rods having inwardly disposed upper and lower extensions secured to the posts, a side rail adjustably mounted on the guide rods, projecting eye means secured to the ends of the rail adjacent the upper edge thereof, the said

eye means being slidably connected to the guide rods, and adjustable members mounted on the ends of the rail near the bottom edge thereof, the said adjustable members when in one of their correspondingly adjusted positions being adapted to rest on the lower extensions of the guide rods, whereby the side rail is supported in a substantially vertical position, and when the adjustable members are in another corresponding adjustable position they are disengaged from the lower extensions of the guide rods.

2. In a bed having upright corner posts, a side rail adjustably mounted between and on two of the corner posts at one side of the bed, a pair of substantially vertical guide rods secured to and spaced from the corner posts on which the side rail is mounted and having upper and lower extensions connecting the guide rods to the said corner posts, slidable members secured to the ends of the rail near the upper edge thereof and arranged in slidably connected relation to the guide rods, and a pair of adjustable supporting devices secured to the opposite ends of the rail at the lower edge thereof, the said devices when in one of their correspondingly adjusted positions being positioned in a supported position on the lower extensions of the guide rods, whereby the rail is supported in a raised position, and the said devices when in another correspondingly adjusted position being released from the lower extensions of the guide rods.

3. In a bed having upright corner posts, a pair of upright elongated guide members supported on the corner posts at one side of the bed, the said guide members being arranged in spaced relation to the corner posts on which they are supported, the said guide members having inwardly disposed upper and lower extensions connecting the guide members to the posts, a side rail adjustably mounted on the guide members and arranged to be supported in an upright raised position between the guide members, a pair of slidable members secured to the opposite ends of the rail adjacent the upper edge thereof and arranged in slidably connected relation to the guide members, and a pair of adjustable supporting devices secured to the lower portion of the rail at the opposite ends thereof, the said devices when in one of their correspondingly adjusted positions being supported on the lower extensions of the guide members, whereby the rail is supported in an upright position, and the said devices when in another of their correspondingly adjusted positions being released from the lower extensions of the guide members, whereby the rail may be lowered and swung under the bed.
